[57] CLAIM

The ornamental design for a light fixture for a ceiling fan, as shown and described.

DESCRIPTION

FIG. 1 is a perspective view of a light fixture for a ceiling fan showing my new design;

FIG. 2 is a front view thereof; the rear-view being a mirror image thereof;

FIG. 3 is a right-side view thereof;

FIG. 4 is a left-side view thereof;

FIG. 5 is a top view thereof;

FIG. 6 is a bottom view thereof; and,

FIG. 7 is a perspective view of the light fixture for a ceiling fan shown in FIGS. 1-6, the broken lines illustrating environmental structure only and forming no part of the claimed design.
